UNITED STATES PATENT OFFICE

ROBERT C. NEWTON, OF NEEDHAM, MASSACHUSETTS, ASSIGNOR TO H. F. LIVERMORE CO.,
OF ALLSTON, MASSACHUSETTS, A CORPORATION OF MASSACHUSETTS

DOBBY LEVER

Application filed July 3, 1930. Serial No. 465,495.

This invention relates to a dobby lever for use in loom dobbies.

Each loom dobby includes a considerable number of dobby levers positioned side by side and close together. Each dobby lever has a hook pivotally attached thereto at each end thereof, and as the space allowed in the dobby for both lever and hook is limited and as both of these members, especially the hook, are subjected to constant and heavy strain, it is necessary that said hook be replaced frequently.

The object therefore of this invention is to provide an improved dobby lever so constructed that if the hook requires replacing and it is necessary to detach said hook from said lever that this may be easily and quickly accomplished without dismantling the dobby.

20 The invention consists in a dobby lever as set forth in the following specification and particularly as pointed out in the claims thereof.

Referring to the drawings:

25 Fig. 1 represents a side elevation of a dobby lever embodying my invention, together with certain portions of a loom harness mechanism that are associated therewith.

30 Fig. 2 is an edge elevation of the dobby lever.

Fig. 3 is a side elevation of an end portion of a dobby lever, the reverse side being shown from that illustrated in Fig. 1.

35 Fig. 4 is an enlarged detail sectional view taken on the line 4-4 of Fig. 1.

Fig. 5 is an edge view of an end portion of a dobby lever illustrating a modified construction.

40 Like numerals refer to like parts throughout the several views of the drawings.

In the drawings, referring particularly to Figs. 1 to 4 inclusive, 5 represents a portion of a harness lever and 6 is a dobby lever which is pivotally attached to the lever 5 at 7. Pivotally attached to the upper and lower extremities of the lever 6 are dobby hooks 8 and 9 respectively, these hooks being of well-known construction. A lifter rod 10 and the end portions of dobby fingers 11 and

12, all of well-known construction, are also illustrated, their operation being well known to those skilled in the art.

The lever 6 is constructed of two similar pieces of sheet metal 13 and 14 which are reversely positioned face to face and permanently secured together at 15 by rivets or any other suitable means. The sheet material of which the parts 13 and 14 are formed is preferably of a flexible character, either being constructed of resilient spring steel or of a soft cold rolled steel that may be flexed.

One end of each member 13 and 14 is offset at 16, thereby providing a space 17 between said member at each end of the layer 6 and in effect forming a bifurcated bearing portion at each end thereof between the furcations of which the hooks 8 and 9 are positioned. The hooks 8 and 9 are each provided with oppositely projecting trunnions 18 and the offset end portion of the members 13 and 14 is slotted at 19 to receive one of the trunnions 18. The other end portion of the members 13 and 14 is slotted at 20 to receive the other trunnion 18 and both of these trunnions constitute pivot members for the dobby hooks.

The end portion of the members 13 and 14 in which the slot 20 is located is also slotted at 21 to form a locking member 22, the end portion of which projects into the slot 20 and is provided with an arcuate extremity 23 which bears against the periphery of the trunnion 18 and holds the latter in said slot.

Only one locking member 22 is required at each end of the lever 6 to securely hold the dobby hook in position in the lever and when it is desired to either attach a dobby hook to the lever 6 or to detach said hook from said lever all that is necessary is to bend or flex the locking member 22, as illustrated in dotted lines in Fig. 2, and the trunnion portions 18 of the hook may be inserted or removed from the slots 19 and 20. If the members 13 and 14 are constructed of resilient material, the locking member 22 will be forced outwardly against the tension of the material and after the hook has been removed from the end of the lever 6, 100

the locking member will spring backwardly to its normal position. If, however, the parts are constructed of soft cold rolled steel, the free end of the locking member 22 will be forced outwardly a sufficient amount to remove the dobby hook from the lever 6, after which it will be necessary to again force the locking lever back to its normal position. Both of the dobby hooks 8 and 9 are attached to and detached from the lever 6 in exactly the same manner and if either of these hooks are broken and need to be replaced, or if it is necessary to replace the lever 6, the hooks may be disconnected from the lever 6 without dismantling any other portion of the dobby.

In Fig. 5 I have illustrated a modified embodiment of my invention in which the opposite end portions of a dobby lever are constructed of two separate pieces of sheet metal 24 and 25, which may be either riveted or welded together at 26. The members 24 and 25 may be constructed either of resilient spring steel or soft cold rolled steel in order that a locking portion thereof may be bent or flexed, but instead of extending the members 24 and 25 from one end of the lever to the other, a separate intermediate portion 27 is provided which is preferably constructed as a forging and the members 24 and 25 are butt welded to the member 27 upon a dotted line that is illustrated at 28 thereby providing a dobby lever that is in effect a single piece. It is evident that several other methods of constructing the end portions of the lever 6 may be employed which will permit metal having different characteristics to be utilized without departing from the spirit of this invention and which will fall within the scope of the appended claims.

I claim:

1. A dobby lever embodying therein bifurcated end bearing portions, the furcations thereof being provided with slots therein to receive the pivot members of a dobby hook, said slots being open at an end thereof, and flexible means adapted to hold said pivot members in said slots.
2. A dobby lever embodying therein bifurcated end bearing portions, the furcations thereof being provided with slots therein to receive the pivot members of a dobby hook, said slot being open at an end thereof, and a flexible locking member adapted to contact with one of said pivot members and hold said hook upon the lever.
3. A dobby lever embodying therein bifurcated end bearing portions, the furcations thereof being provided with slots therein to receive the pivot members of a dobby hook, and a locking member projecting into the slot of one of said furcations and adapted to contact with the pivot member therein,

whereby both of the pivot members are held in position in their respective slots.

4. A dobby lever embodying therein bifurcated end bearing portions, the furcations thereof being provided with slots therein to receive the pivot members of a dobby hook, and flexible means integral with one of said furcations and projecting into one of said slots and adapted to contact with the pivot member therein, whereby both of the pivot members are held in position in their respective slots.

5. A dobby lever comprising similar members constructed of sheet metal fastened together face to face, each member being offset at one end thereof and co-operating with the end portion of the adjacent member to form end bearing portions, both of the latter being provided with slots therein to receive the pivot members of a dobby hook, and flexible means projecting into one of said slots and adapted to contact with the pivot member therein, whereby both of the pivot members are held in position in their respective slots.

In testimony whereof I have hereunto set my hand.

ROBERT C. NEWTON.
